UNITED STATES PATENT OFFICE.

JOSEPH BOULET, OF BEVERLY, MASSACHUSETTS.

GEAR-TOOTH CALIPERS.

SPECIFICATION forming part of Letters Patent No. 643,080, dated February 6, 1900.

Application filed October 30, 1899. Serial No. 735,166. (No model.)

To all whom it may concern:

Be it known that I, JOSEPH BOULET, a citizen of Canada, residing at Beverly, in the county of Essex and State of Massachusetts, have invented a new and useful Improvement 5 in Gear-Tooth Calipers, of which the following is a specification.

My invention relates to improvements in micrometer-calipers specially adapted to the measurement of gear-teeth, the object of which is to provide means for conveniently and accurately measuring such teeth on the pitch-line and at the same time correctly locating the measuring-points on such line, thereby 15 detecting very minute variations from the true form of the teeth which may occur from imperfect cutters or cutting operations. I attain said object by the mechanism illustrated in the accompanying drawings, in which—

20 Figure 1 is an elevation of my improved calipers and includes also an illustrative section of a gear introduced to show the manner of applying the measuring-tool or calipers to the teeth when in practical use. Fig. 2 is an under side view of the calipers. Fig. 3 is a central longitudinal section taken horizontally through Fig. 1. Fig. 4 is a cross-section taken as on line $x-x$, Fig. 1. Fig. 5 is a cross-section taken as on line $z-z$, Fig. 1, and viewed 25 from the right of said line. Fig. 6 is an enlarged sectional view showing the construction of the spindle-bearing, which is also shown in Fig. 3.

The calipers as illustrated in said drawings 30 comprises a micrometer composed of telescopic shells A and B, arranged to slide one upon the other in a well-known manner and marked with indicating-scales in the usual way; a central spindle C, which extends 35 through the outer end of shell A and is clamped thereto by means of a shoulder and nut on the spindle, as shown in Fig. 3, the spindle being also threaded into shell B and having a bearing in a projection which supports its opposite end; a bar D, which is firmly 40 attached to the outer end of shell B, being fitted and properly secured in a groove in the head B', formed upon and as an integral part of said outer end of shell B, as shown in Figs. 45 1, 2, and 3, and through which spindle C passes, as shown in Fig. 3; a slide or carriage E, mounted upon said bar and provided with a

locking-screw E'; a movable jaw F, attached to slide E, and a coöperating fixed jaw F', secured to the outer end of bar D. There is 55 also mounted upon bar D, between the jaws F and F', a micrometric locating-gage arranged at right angles to the bar and to slide thereon. This locating device comprises two telescopic shells G and H, marked with indicating-scales and provided with a central spindle attached to the upper end of shell G and threaded into the interior of shell H and operating to indicate the measured movement 60 of the locating spindle or gage I in substantially the same well-known manner as the first herein-described micrometer operates.

The novelty which constitutes my invention consists in the combination of the two micrometers with adjustable measuring-points under the peculiar construction and mode of operation which I will now describe, and point out in the appended claims.

A projection J (see Fig. 5) extends outward from the face of slide E and carries a threaded 75 bushing K, which is screwed into said projection and serves as a bearing for the end of spindle C, as shown in Figs. 3 and 6. A shoulder C' on the spindle bears against the enlarged end of said bushing, which serves as a journal-bearing for the projecting end of the spindle. Into this end is screwed an extension-spindle C², up to a shoulder C³ thereon, which bears 80 against spindle C opposite shoulder C'. The extension-spindle C² thus secured in the end 85 of spindle C serves as a practical continuation of the latter, but the screw-threads cut thereon are but one-half the pitch of the threads on the main spindle C and are threaded into a projection M on the sliding block which 90 carries the locating-gage I. By this construction when spindle C is turned to move slide E in either direction a differential movement is produced, and the locating-gage I will be moved by the spindle only half the distance 95 that slide E, with its jaw F, is moved thereby, and therefore to whatever distance apart jaws F and F' may be thus adjusted the locating-gage I will always be moved by spindle C² to a position exactly midway between 100 the jaws. The projection J, being divided at its outer end, a screw L is threaded through the parts thereof and serves as the means by which the bushing K may be secured against

turning in its place by thereby pinching the divided branches of the projection together upon the bushing.

In Fig. 1 the calipers is illustrated as when 5 in practical use on a gear-tooth P, the locating-gage I being properly adjusted by its micrometer to bear upon the top of the tooth, as shown, and in such relation to the measuring-points of the coöperating jaws F and 10 F' as to locate them accurately on the pitch-line P' of the tooth the thickness of which is to be measured by them. Thus when the calipers is adjusted to give the correct dimensions required any variation therefrom arising 15 from the use of an imperfect cutter or otherwise may be readily detected and measured even to one-thousandth of an inch.

The locating-gage is micrometrically adjustable longitudinally relatively to the tooth to 20 be measured and independently of the adjustment of the jaws relatively to each other, while by a separate micrometer the jaws are adjustable in relation to each other and the locating-gage is at the same time and by the 25 same means adjustable in its central position between the jaws whatever their distance apart may be.

I claim—

1. A caliper, embodying the combination of 30 a supporting frame or bar; a micrometer attached to the bar; a jaw the movements whereof upon the bar are regulated and measured by said micrometer attachment; a coöperating jaw immovably attached to the bar; a locating-gage mounted upon the bar midway 35 between the jaws and extending at right an-

gles to, and movable laterally upon, the bar; and a micrometer attachment to the locating-gage for regulating and measuring its longitudinal movements; all substantially as set forth.

2. A caliper embodying the combination of a pair of jaws, one fixed and the other movable; means for micrometrically adjusting and measuring the movement of the movable 45 jaw; a locating-gage midway between the jaws adjustable at right angles to the movement of the jaw, and also movable in the same direction therewith; means for micrometrically effecting such adjustment of the gage; 50 and means for simultaneously moving the gage with the jaw and in the same direction, but differentially so as to maintain it in a constant central position between the jaws; all substantially as and for the purposes specified.

3. In combination, bar D; jaws F and F', thereon, one fixed and the other movable; locating-gage I, placed centrally between the jaws upon the bar, and being adjustable at 60 right angles to, and arranged to also slide upon, the bar; the threaded spindle C, C² constructed and arranged to impart differential movements to jaw F, and gage I, upon the bar, simultaneously and in the same direction; and micrometer devices for measuring and indicating the movements of the jaw and gage; all substantially as specified.

JOSEPH BOULET.
